Specification for Design.

Patented May 24, 1921.

Application filed August 11, 1920. Serial No. 402,915. Term of patent 7 years.

To all whom it may concern:

Be it known that I, HERBERT A. KAITTING, a subject of the King of Great Britain, residing at the city of Galt, in the county of Waterloo, in the Province of Ontario, Canada, have invented a new, original, and ornamental Design for a Bracket for Windshield-Blinds, of which the following is a specification, reference being had to the ac-

companying drawing forming part thereof, in which—

Figure 1 is a front elevation of the bracket; and

Fig. 2 is an end view.

I claim:

The ornamental design for a bracket for windshield blinds, as shown.

HERBERT A. KAITTING.
